PORTABLE PICNIC CABINET

James H. Woods, San Fernando, Calif.

Application March 1, 1932. Serial No. 595,997

6 Claims. (Cl. 190—12)

This invention relates to and has for an object the provision of an improved type of portable picnic cabinet adapted to be detachably supported on the running board of an automobile and provided with the sides which are capable of being removed from the cabinet and operatively supported thereon for forming a table, together with means for enclosing the cabinet when it is not in use.

Another object is to provide a simple, compact and economical cabinet of the character described subdivided into compartments of suitable form and number for carrying different kinds of utensils, dishes, articles of food and the like, and capable of being used as a table while it is supported on the running board of a vehicle or when detached from the vehicle.

I have shown a preferred form of device in the accompanying drawings, in which

Fig. 1 is a perspective view of my assembled cabinet detachably mounted on the running board of a vehicle.

Fig. 2 is a sectional elevation of the same on line 2—2 of Fig. 1.

Fig. 3 is a fragmentary sectional plan on line 3—3 of Fig. 2.

Fig. 4 is a perspective view of the table with the cover removed and the sides detached and operatively supported on the top of the cabinet for forming a table.

Fig. 5 is a fragmentary bottom plan of the cabinet showing the legs and braces therefor folded compactly on the bottom of the cabinet whereby the same may be held on the running board of a vehicle.

The cabinet is provided with a flat bottom 1, a flat top 2, and parallel ends 3 and 4 suitably secured together and preferably formed of light but strong and durable wood. A pair or more horizontal partitions 5 and 6 are provided between the bottom 1 and top 2, as shown in Fig. 2, which may extend either entirely or partially across the cabinet from end to end, depending upon the size, character and number of compartments desired within the body of the cabinet.

As shown in Fig. 4, vertical partitions 7, 8 and 9 are provided at diversely spaced points between the ends 3 and 4 and the partitions 5 and 6 may extend, as shown in Fig. 4, only between the vertical partitions 8 and 9. Other similar partitions, as at 10 and 11, may extend between the end 4 and partition 9 and the partitions 7 and 8 respectively.

The bottom of the cabinet is provided with an encompassing member 12 of right angular cross

section, the lower web 13 of which is spaced from the bottom 1 by means of longitudinal cleats 14, 14 at the front and back. Said cleats extend outwardly from the front and back of the cabinet so as to space the vertical webs 15 of the member 12 from the front side 16 and the rear side 17. Similarly the web 15 of member 12 is spaced from the ends 3 and 4. Thus, a rectangular metal housing 17' which is open at the bottom and is provided with top, side and end portions is adapted to completely enclose the cabinet when the lower edge thereof is seated in the space between the web 15 of member 12, and the cover in such case rests upon the cleats 14.

Metal corner members 18, 18 etc., of right angular cross section are provided at each of the corners of the cabinet and are attached to the ends 3 and 4 as shown in Fig. 3 by suitable means. The front and rear webs 19 of the members 18 are spaced, however, from the edges of the ends 3 and 4 so as to provide seats for the ends of detachable front and rear side members 20 and 21. The bottom 1 projects outwardly from the side edges of the ends 3 and 4 so that the members 20 and 21 will rest upon the bottom when said members are positioned on the cabinet and said members when so positioned extend slightly above the top 2, as shown in Fig. 2.

The ends 3 and 4 are provided at the top with metal members 22 of right angular cross section, the vertical webs 23 of which are attached to the ends 3 and 4 and the horizontal webs 24 of which are spaced from and overlie the top 2.

When the cover 17' is removed from the cabinet the sides 20 and 21 may be detached by sliding the same upwardly and thereafter said members may be positioned as shown in Fig. 4, in which position they are held between the top 2 and the overlying guides 24, 24. When and if desirable, only one of the members 20 or 21 may be thus supported on the cabinet thereby providing a narrow table, or both sides may be supported as shown for providing a wider table.

The compartments formed within the cabinet between the several horizontal and vertical partitions may be provided with metal drawers, as at 25, 26, 27, 28 and 29, etc., of various sizes for various purposes. Any or all of said drawers may be subdivided into smaller compartments, as may be desired, the form, size and arrangement of the compartments being immaterial to my invention.

The cover 17' is provided with lifting devices 30 at the ends, whereby the cover may be removed from the cabinet, and with latches as at 31 also mounted on the ends for detachably securing the

100

105

110

cover to the bottom of the cabinet. The cover is especially desirable for enclosing the cabinet and its contents against the atmosphere and the elements when it is being transported from place to place on the running board 32 of a vehicle.

A pair of legs 33, 33 are provided on the bottom 1 at each end of the cabinet, which are transversely braced by bars 34 and are diagonally braced by toggle brace members 35 and 36 pivoted at 10 respectively to the bottom 1 and the legs 33, as shown in Fig. 4. The legs are also pivoted at their upper ends to the bottom 1 of the cabinet. Thus the legs may be folded upwardly into snug contact with the bottom 1 and within the member 12, as shown in Fig. 2.

To the legs or to the bottom 1 suitable clamps 37 may be attached for frictionally securing the cabinet to the running board 32 of a vehicle. Said clamps include screws 38 which are held in the 20 ends of the clamps and frictionally engage the lower side of the running board, as shown in Fig. 3. The clamps are preferably arranged so that they may be extended as shown in Fig. 2 for attaching the cabinet to the running board of 25 a vehicle, or they may be folded with and within the plane of the legs 33 so that the cabinet may rest upon the ground or other supporting surface firmly before the legs are extended.

As shown in Fig. 5, the legs 33 are pivotally attached at 39 to lugs 40 formed on and depending from bars 41 which are secured to the bottom 1 of the cabinet. Similarly the upper members 35 of the toggle braces are pivoted at their upper ends to lugs 42 which are formed on and depend 35 from the transverse bar 43 secured to the bottom of the cabinet. The clamping member 37 is supported on each pair of legs 33, 33 as shown in Fig. 5.

Suitable handles 44 may be provided on the 40 ends 3 and 4 of the cabinet for lifting and carrying the cabinet from place to place.

It will be quite apparent that when the cover 17' is removed either one or both of the sides 20 and 21 may be detached and supported on the 45 top of the cabinet for forming a table without removing the cabinet from the vehicle.

The assembled outfit is of light weight and conveniently arranged to carry all of the necessary equipment for picnic and camping expeditions and parties, etc., and is weatherproof when the cover 17' is clamped thereon.

The advantages of the structure and arrangement of parts herein shown and described will be readily apparent to those skilled in the art, 55 and it is obvious that I may modify the struc-

ture and arrangement thereof within the scope of the appended claims without departing from the spirit thereof.

What I claim is:

1. A picnic cabinet comprising spaced bottom and top portions and end portions connecting the same, guides secured to and spaced outwardly from the front and rear edges of said ends, and front and rear side members slidably and detachably held in the spaces between said guides and said ends forming closures for the cabinet, and means at the top of the cabinet for slidably supporting said detachable sides when the cabinet is opened to form a table. 80

2. A picnic cabinet as characterized in claim 1, including a base member surrounding the bottom of the cabinet and spaced therefrom providing a recess between the base member and the bottom entirely around the cabinet, and a cover detachably supported on and for enclosing the cabinet when said front and rear sides are positioned thereon between said ends and said guides, the lower edge of said cover adapted to seat in the recess between said base and said bottom. 90

3. A picnic cabinet comprising spaced top and bottom members, end members attached thereto having their front and rear edges terminating short of the front and rear edges of said bottom, guides attached to and spaced from the front and rear edges of the end members, and front and rear members detachably and slidably supported in the spaces between said guides and said end members and adapted to be supported on the extended portions of the bottom. 100

4. A picnic cabinet as characterized in claim 3, including a base secured to the bottom and spaced therefrom entirely around the cabinet providing a channel externally of the cabinet, and a cover enclosing said cabinet and having its lower edge seated in said channel. 110

5. A picnic cabinet as characterized in claim 3, including guides attached to the extremities of said ends and overlying said top providing ways for slidably supporting said front and rear members horizontally on the top of said cabinet to form a table. 120

6. A picnic cabinet comprising spaced bottom and top portions, end members connecting the same, side members detachably supported on said end members for closing the front and rear sides of said cabinet, and guides supported on the end members and overlying the top of the cabinet for slidably supporting said side members to provide a table when the cabinet is open. 125
